UNITED STATES PATENT OFFICE.

HENRY RIDGEWAY HART, OF MONTCLAIR, NEW JERSEY.

COMMUNICATING HELMET.

Application filed October 17, 1925. Serial No. 62,952.

This invention relates to helmets having associated therewith means whereby communication may be had with the wearer vocally which is not subject to interruption 5 in aircraft, for instance, by the roar of the propeller, air pressure, etc. The invention has for its particular object to associate with a helmet of improved design means whereby communication in ordinary tones may 10 be had with the wearer of the helmet or between the respective wearers of two helmets. To this end the invention resides in the specific combination and arrangement of parts hereinafter more fully described 15 and claimed. In the accompanying drawings illustrating preferred embodiments of the invention:

Figure 1 is a view showing a pair of inter-communicating helmets and means whereby 20 the wearers of the helmets may carry on a conversation.

Figure 2 is view on an enlarged scale showing the mouth piece for the communicating devices.

Figure 3 is a transverse vertical sectional view in detail, of the air piece serving to insulate the ear from extraneous sound.

Figure 4 is a view showing the invention as applied to a one-way communicating helmet.

Figure 5 is an enlarged front view showing a modified form of the helmet according to the present invention.

Figure 6 is a side view on a smaller scale 35 showing the helmet according to Figure 5.

In the drawings two individuals between whom communication is to be had are indicated at α and X . Each individual is provided with a helmet a , A which are identical 40 in structure. Carried with each helmet are ear pieces b , b , B , B . Also carried with each helmet is a mouth piece c , C . Between the two individuals α , X , there may extend a common flexible conduit d having 45 a single passage d' therethrough. At either end of conduit d there is carried a three-way connector e , E having branch passages f , f' , F , F' connecting the ear pieces b , B with the connections e , E . Connecting the mouth 50 piece c , C with the connections e , E are tubes g , G . It will thus be seen that if the individual indicated at α wishes to communicate with the individual indicated at X he may speak in ordinary tones into the 55 mouth piece c and the sound waves will travel through the tube g , common conduit

d and tubes F , F' to the ear pieces B worn by the wearer X and vice versa when the individual indicated at X desires to converse with the wearer α . In some instances as with an instructor and pupil it may be found desirable to have only one-way communication in which instance a pupil indicated at y and wearing the helmet a may receive vocal instructions from an 60 instructor wearing the mouth piece c . As no mouth piece is provided for the student flyer a two-way connection i is provided between the conduit d and the ear piece tubes f . 65

The mouth piece, which is flexible, for 70 use in connection with either the one-way or the two-way communicating helmets is shown on an enlarged scale in Figure 2. It comprises a flexible fabric cover for the mouth indicated in general at c suitably 75 hemmed as at c' and terminating in the lowermost portion thereof in a cylindrical outlet c^2 adapted to receive the flexible tube g which in the illustrated embodiment is formed inwardly of the cylindrical portion 80 with an enlarged end g' beveled at either end as at g^2 and of sufficient length to terminate adjacent the mouth of the wearer. The side extensions which are intended to 85 overlie the wearer's lip and which have been given the reference character c^3 are provided with eyelets c^4 suitably reinforced as with leather at c^5 for the reception of an elastic strap h provided with adjustable devices shown in Figure 4 at h' . The elastic 90 retaining means h may be readily worn over the ear pieces b as shown in Figure 1.

The helmet as shown in Figures 1 and 4 may be of the flexible variety formed of a series of panels of soft leather a' suitably 95 shaped and stitched to conform to the head of the wearer and in Figure 3 the helmet is shown as comprising an outer layer of flexible leather a^2 suitably faced inwardly with leather binding a^4 along the edges. 100 The lining is adapted to be secured to the interior of the helmet by snap fasteners a^5 whereby the inner lining a^3 of warm material may be removed in warm weather in the interest of comfort. The warm inner 105 lining a^3 is provided with apertures a^{3y} suitably bound with leather as at a^{3y} in order to fit about the cushion b' of the ear piece.

The ear piece may comprise in general a 110 metallic elbow b^2 to which the flexible conduit f is secured and which in turn is con-

nected to an annulus b^3 having an annular groove b^4 for the reception of a circular aperture b^5 formed in a cup-shaped leather closure b^6 for the ear piece which closure is preferably formed of stiff leather and is turned downwardly as with a flange at b^7 to be secured to the edges of an aperture a^{5x} formed in the helmet a . Between the cup-shaped member b^6 and the annulus b^3 there is disclosed the cup-shaped cushioning element b' hereinbefore referred to. This cushioning element may be formed of any convenient material, a species of sponger rubber being found most practical. Means are also provided for retaining the ear pieces in snug engagement with the wearer's ears. In the illustrated embodiment in addition to a chin strap indicated in general at a^6 , straps are provided shown at a^7 which are adapted to be threaded through buckles a^8 at the crown. Similar buckles a^9 are also shown carried with the forehead portion of the helmet which are adapted to secure forwardly extending straps a^{10} and similarly there may be disposed straps extending rearwardly from the ear pieces to buckles disposed on the helmet in proximity to the base of the skull.

The invention may also be incorporated 30 in a rigid helmet adapted to afford a degree of protection in case of accident. Such helmet is indicated in Figures 5 and 6 at j and may comprise sections j' of sole leather suitably formed and stitched to conform to the 35 head of the wearer and extending downwardly in the rear as at j^2 to protect the base of the skull of the wearer. An additional re-enforcement at the top as at j^3 may also be provided. The helmet may be lined 40 with any soft cushioning material, such as sheepskin, with the wool inwardly.

The helmet may be cut away as at j^4 to 45 accommodate the ears and at that portion may have extended thereacross a strap j^5 cut away, if desired, at j^{5x} to give greater freedom of movement of the ear pieces. Immediately above the strap there may be disposed buckles j^6 . The ear pieces may 50 comprise cups k of stiff leather having flanges k' continuing at one point into straps k^2 adapted to thread into the buckles j^6 . Diametrically opposite the straps k^2 there may

be secured a ring k^3 for the reception of an adjustable chin strap l carrying a broad band of soft leather l' adapted to engage the 55 chin. The cups k carry as in the previously described embodiment elbows b^2 which terminate in annuli b^3 , not shown, and which are spaced from the wearer's ear by the cushions b' . As further means for retaining the ear 60 pieces in snug engagement with the wearer's ears, there is provided at the front of the helmet buckles j^7 adapted to co-operate with a strap m extending through loops k^4 and on the cups k and adapted to engage the rear 65 of the wearer's neck at which point the strap may be provided with a soft leather bearing surface m' .

It will thus be seen that an extremely practical communicating helmet or inter-connecting helmets has or have been provided whereby communication may be had vocally in ordinary tones between the respective wearers under conditions of high wind or loud noise and such helmets and the associated 75 parts may be adopted for wear in circumstances of warmth or cold suitable re-enforcement of the helmet being provided in the interest of safety to the wearer, if desired.

What I claim is:

In combination with a helmet having a head portion, ear pieces formed with the head portion and adapted for the reception of cushioning elements, means to retain the 85 ear pieces in close contact with the wearer's head, conduits for the ear pieces, means to removably connect the ends of said conduits to the ear pieces and to removably secure the cushioning elements, a mouth piece comprising flexible material adapted to fit snugly upon a substantial portion of the wearer's 90 face adjacent the mouth, means carried with the helmet to keep the mouth piece in place upon the wearer's face, a conduit for the 95 mouth piece, means to connect said conduit to the mouth piece, and means connecting the conduits for the ear pieces with each other and with the conduit for the mouth piece and with another conduit.

This specification signed this 16th day of October, A. D. 1925.

HENRY RIDGEWAY HART.
